UNITED STATES PATENT OFFICE.

EMANUEL S. ULLMANN, OF NEW YORK, N. Y.

APPARATUS FOR MOORING AIRSHIPS.

1,351,931.

Specification of Letters Patent. Patented Sept. 7, 1920.

Application filed September 4, 1919. Serial No. 321,526.

To all whom it may concern:

Be it known that I, EMANUEL S. ULLMANN, a citizen of the United States, and a resident of the borough of Manhattan, in the city and State of New York, have invented certain new and useful Improvements in Apparatus for Mooring Airships, of which the following is a specification.

My invention relates to devices and means 10 for mooring or anchoring airships of various types, whether lighter or heavier than air, being more particularly intended for securing the type of airships commonly called dirigible balloons or "dirigibles", although 15 the same is also adapted for mooring aeroplanes.

The object of the invention is to provide 20 means whereby such an airship, having arrived at a stopping place, may be easily moored to the ground in an expeditious and 25 secure a manner, and released in order to renew or resume its journey.

The invention consists in the novel construction, arrangement and combination of 25 various devices and parts, as hereinafter defined in the claims.

In the said drawings Figure 1 is a general 30 view showing a side elevation of a dirigible balloon of ordinary type and showing, partly in section, a portion of the means by which the same is moored to the ground; Fig. 2 is a plan view of the same; Fig. 3 is a side elevation on an enlarged scale, partly in section, of the said mooring devices; Fig. 4 is a plan view of the same; Fig. 5 is a detail view hereinafter described; Fig. 6 is a side elevation and Fig. 7 a plan view of a modification of the device adapted to receive and secure an aeroplane, and Figs. 8, 9 and 10 are detail views hereinafter fully described.

It is well known that in the case of an ordinary dirigible balloon particularly, and also in a less degree perhaps in the case of 45 an aeroplane, when the same arrives at a stopping place, especially if any appreciable degree of wind prevails at the time, considerable difficulty is experienced in mooring the airship to the ground in such a manner 50 as to securely hold the same and at the same time without injury. If the airship is a moderately large one, and if the prevailing wind is strong, and especially if the same is variable as to force or direction, the mooring 55 of the dirigible and the continued hold-

ing of the same in a safe position, becomes a very difficult and even dangerous proceeding, requiring the services of a great number of men and the supervision of experienced and skilled directors of the work. 60 It is considered necessary to keep the dirigible pointed up into the wind, and to allow the rear portion to swing around from side to side as the varying currents of air strike the same, at the same time holding the rear portion down by ropes of considerable length. Unless the lower ends of these securing ropes are swung around corresponding to the swinging motion of the rear portion of the dirigible, the latter would be 65 dashed to the ground and injured, and the only method which has thus far been employed for accomplishing this purpose is to have the lower ends of the various ropes held by a sufficient number of men to hold the 70 dirigible down, who travel around to different parts of the field as the wind swings the dirigible into different positions, in order to maintain the lower or mooring end of the rope approximately underneath the body of 75 the dirigible, and this continual supervision must be continued until the dirigible can be drawn into a suitable hangar, if one be present; if no hangar is in existence, the personal manual management of the dirigible 80 must be continued during the whole time of its stay on the field and until it resumes its journey. My invention seeks to provide a safe and secure mechanical method of mooring the dirigible, which will allow it to 85 swing freely in any direction into which the wind may impel the same.

In carrying my invention into effect in the embodiments thereof which I have selected for the purpose of description in this specification and illustration in the accompanying drawings, and referring first to the particular embodiment which is shown in Figs. 1 to 4 inclusive of the accompanying drawings, which embodiment is designed more 90 particularly for the reception of the lighter-than-air airship or "dirigible", I provide at or near the central part of a suitable open space of a size proportioned to the length of the dirigibles which are expected to be 95 moored, a stationary device 11, which may be of any suitable construction, as for instance a wedge-shaped post of concrete, or reinforced concrete, or the like, securely embedded in or secured to the ground. Bolted 100 110

or otherwise suitably secured to the upper part of the post 11 is a plate 12 (see particularly Figs. 3 and 4) the upper surface of which is provided with an annular channel for the reception of ball bearings 13. I further provide a swinging mooring member, pivotally secured to said plate 12, consisting of a pair of channel-irons 14 connected and braced by members 15. The inner ends of the angle-irons 14 are rigidly secured to a member 16, the lower surface of which is channeled to receive the ball bearings 13 and which is adapted to rotate upon said ball bearings, and is pivotally secured to the plate 12 by a bolt 17 or in any suitable manner. To the other side of the member 16 are secured similar, though shorter, channel-irons 18, secured and braced together similarly to the channel-irons 14.

In a circular line around the central post 11, and at a distance therefrom approximately equal to the length of the channel-irons 14 I provide at suitable intervals posts 20 substantially similar in construction to the post 11. Supported upon these posts 20 is a stationary guideway consisting in the form illustrated of a circular channel-iron 21, extending, either continuously or in a number of sections as may be most convenient, all around the circle, a break in the upper portion of which is preferably provided at some part of the circle, which is covered by a removable plate 22, which can be taken off for the purpose of lifting out the swinging mooring member should the same be necessary for the purpose of repairing the same or otherwise.

To the outer ends of the channel-irons 14 is secured a member 23 in which are journaled wheels or rollers 24, 25 and 26, which bear respectively against the upper, outer and lower parts of the channel-iron 21.

The said swinging mooring member is provided with a series of rings 27, on the portion thereof formed by the channel-irons 18 as well as that formed by the channel-irons 14, said rings being adapted to receive the cables 28 or other means (see Fig. 1) by which the dirigible is to be moored. These rings 27 are preferably connected to the bracing members 15 by means of a swivel 29, as shown more particularly in the detail view Fig. 6.

The operation of this embodiment or modification of my invention will, I think, be sufficiently obvious from the above description of its construction. It will be clear that the swinging mooring member composed of channel-irons 14 and 18 with their strengthening bracing members, and to which the dirigible is moored as above described, being pivotally secured to the central post 11, is free to swing around into any position into which the dirigible secured thereto may be impelled by the wind

currents, and that the outer end of the mooring member is securely held by means of the channel-iron 21 against upward movement. It will readily be seen that by employing this construction the dirigible may be securely moored and yet be perfectly free to swing in response to varying directions of the wind, in such a manner as to prevent any injury to the same, while mooring it as long as required and yet permitting the same to be quickly released when it is desired that the same should resume its journey.

In carrying into effect my invention in the embodiment or modification which is shown in Figs. 6 and 7, which is adapted more particularly for the reception of aeroplanes or heavier-than-air machines, I provide a central post, here designated 40, a series of circumferential posts 41, a swinging mooring member comprising channel-irons 42 and 43 and bracing members 44; also a circumferentially arranged channel-iron 45 in which the outer end of the swinging mooring member runs, the same being provided with wheels or rollers 46, 47 and 48, all of which are analogous to and operate in the same manner as corresponding parts in the embodiment of my invention which has already been described. In this form of my invention, however, I provide certain additional elements as follows: To the channel-irons 42 I secure a superstructure comprising members 50 upon which are supported transverse beams 51 which in their turn support longitudinal beams 52, which are channeled or grooved to form trackways for the wheels of an aeroplane.

The longitudinal beams 52 are secured to the transverse beams 51 by means of bolts 53 which pass through the beams 52 and engage with slots 54 in the transverse beams 51, this construction permitting the longitudinal beams 52 to be adjusted at various distances from each other so as to accommodate the wheels of different sizes of aeroplanes. Ropes or similar securing devices 55 are provided to prevent the longitudinal beams 52 from separating too far, and said beams 52 may be securely attached at any desired position upon the transverse beams 51 by tightening the nuts of the bolts 53 in a manner which will be obvious.

The outer ends of the beams 52 are, as is clearly shown in Fig. 6, elevated sufficiently to clear the channel-iron 45 when swinging around, and in order to connect these elevated outer ends with the ground I provide members 56, hinged to the members 52 at 57, and channeled similarly to the members 52, which when in the lowered position shown in Fig. 6 are adapted to permit the aeroplane to be rolled up or down thereupon to or from the members 52, but which when the aeroplane is upon the members 52 may

be hinged upward so as to clear the ground and allow the apparatus to swing into any position, as it may be impelled by the changing direction of the wind. A series of rings 5 58 are provided upon the beams 52, to which cables or similar devices 59 may be secured for mooring the aeroplane in position, as shown in Fig. 6.

10 The members 56 may, instead of being hinged to the members 52, be secured in any suitable manner, and if desired in such a way as to be easily removable therefrom after the aeroplane has been rolled upon the superstructure and laid aside until needed, 15 when they may be replaced.

In order to insure the proper swinging of the device, so that the aeroplane may always present its head to the wind, I provide the devices shown more particularly in Figs. 8, 20 9 and 10 (on an enlarged scale). These comprise a frame 60, provided at its lower part with tongues or tenons 61 adapted to be inserted in sockets at 62 in the longitudinal beams 52. This frame 60 is covered 25 with sail-cloth 63 or other suitable material, and the devices, one for each side, when in place on the beams 52, form vanes upon which the wind may act in order to swing the apparatus around.

30 The operation of this embodiment of my invention will be entirely obvious from what has already been said, and I do not think it necessary to describe the same more particularly.

35 It will be obvious that my invention may be constructed in various other forms and embodiments without departing from the spirit and scope of the same. The particular type of foundation structure or swinging 40 mooring member, or any of the other parts, is not essential, and any substantially similar form of the same may be employed. I consider that the spirit of my invention involves the provision of a pivotally secured 45 device to which the dirigible or aeroplane may be secured and which is free to swing in any direction as the dirigible or aeroplane is acted upon by varying currents of wind.

50 The advantages of my invention have been particularly pointed out in the above description of the same, and will be clearly obvious from what has been above said, and I do not think it necessary to treat further of the same.

55 Having thus described my invention, what I claim as new and desire to secure by Letters Patent is as follows:

1. An apparatus for mooring airships 60 comprising a fixed support, a pivoted mooring member mounted to turn on said support and provided with means for the engagement of the mooring ropes of an airship, and means for holding said mooring member against upward movement, including a stationary guideway in which the outer por-

tion of said mooring member is adapted to travel and by which it is held against upward movement.

2. An apparatus for mooring airships comprising a fixed support, a pivoted mooring member mounted to turn on said support and provided with means for the engagement of the mooring ropes of an airship, and means for holding said mooring member against upward movement, including a circular stationary guideway in which the other portion of said mooring member is adapted to travel and by which it is held against upward movement. 70

3. In an apparatus for mooring airships, the combination with a mooring member, of devices adapted to secure the same pivotally to the ground, and devices at one end of said mooring member adapted to secure the same against upward movement: said devices comprising a circumferentially located channel member adapted to receive in its channel the outer end of said mooring member and secure the same against vertical movement while permitting the same to swing laterally 85 in either direction.

4. In an apparatus for mooring airships, the combination with a mooring member, of devices adapted to secure the same pivotally to the ground, and devices at one end of said mooring member adapted to secure the same against upward movement: said devices comprising a circumferentially located channel member adapted to receive in its channel the outer end of said mooring member and 90 secure the same against vertical movement while permitting the same to swing laterally in either direction, said mooring member being provided with a roller at said outer end 95 adapted to bear against said channel member. 100

5. In an apparatus for mooring airships, the combination with a mooring member and devices adapted to secure the same pivotally to the ground, of a superstructure upon said mooring member adapted to receive and support an aeroplane, and devices swingingly attached to said superstructure and adapted when in a lowered position to bridge the space between the outer end of said superstructure and the ground whereby an aeroplane may be moved from the ground to said superstructure and vice versa. 110

6. In an apparatus for mooring airships, the combination with a mooring member and devices adapted to secure the same pivotally to the ground, of a superstructure upon said mooring member adapted to receive and support an aeroplane, and devices removably secured to said superstructure and adapted when in position to bridge the space 115 between the outer end of said superstructure and the ground whereby an aeroplane may be moved from the ground to said superstructure and vice versa. 120

7. An apparatus for mooring airships 125

- comprising a fixed support, a swinging mooring member pivoted to said support and provided with means for the engagement of the mooring ropes of an airship, beams 5 mounted on said swinging mooring member and extending transversely on opposite sides thereof, longitudinal beams mounted on said transverse beams and provided with grooves adapted to receive the ground wheels of airplanes, and means for holding said swinging member against upward movement, while permitting the lateral swing thereof, including a fixed member engaged by said swinging member. 10
- 15 In an apparatus for mooring airships, the combination with a mooring member and devices adapted to secure the same pivotally to the ground, of a superstructure upon said mooring member adapted to receive and support an aeroplane, comprising a plurality of transverse beams secured to said mooring member and a plurality of longitudinal beams adjustably secured to said transverse
- beams and adapted to support an aeroplane or the like. 25
9. An apparatus for mooring airships comprising a fixed support, a pivoted mooring member mounted to turn on said support and provided with means for the engagement of the mooring ropes of an airship, means 30 for holding said mooring member against upward movement, including a stationary guideway in which the outer portion of said mooring member is adapted to travel and by which it is held against upward movement, a superstructure upon said mooring member adapted to receive and support an airplane, and means mounted upon said superstructure independently of such airplane and adapted to be acted upon by air 35 currents to swing said mooring member and its superstructure laterally. 40

Signed at New York city, this 3d day of September, 1919.

EMANUEL S. ULLMANN.
